UNITED STATES PATENT OFFICE.

SIGMUND GREENFIELD, NOW BY JUDICIAL CHANGE OF NAME EDWARD S. GRANDT, OF NEW YORK, N. Y.

DISPENSING TOP FOR CONTAINERS.

Application filed September 11, 1925. Serial No. 55,657.

This invention relates generally to a construction of dispensing tops for containers and more particularly to a dispensing top or closure member for collapsible tube containers.

A general object of the invention is to provide a closure member for containers more particularly of the collapsible tube type in which provision is made for producing a tight or closely sealed effect when the device is in non-delivering condition.

The invention includes a delivery or discharge nozzle for the tube container having a conical formation with a discharge port in one of the side walls thereof. A closure member is fitted to the conical discharge member with the edge thereof spun or upset into locking relation with the base of the conical discharge member, the closure member being rotatable about the discharge member on which it is supported to thereby bring an opening in the side wall thereof into and out of registration with the delivery opening in the nozzle member.

In a preferred embodiment of the invention the discharge member and the closure member have an unsymmetrical or eccentric formation designed to produce a binding or sealing effect between the walls of the members immediately about the openings when the openings are moved out of registration with each other. This results in the attainment of a complete and adequate sealing effect in the non-operative position of the closure member so that the mere rotation of the closure member in either direction to non-operative position has the effect of closely sealing the edges of the opening to thereby preserve the contents of the container.

Other features of the invention will be hereinafter referred to.

In the drawings,

Figure 1 is a view in side elevation of a collapsible tube container equipped with a dispensing top embodying the invention.

Figure 2 is an enlarged sectional view of the dispensing top portion of the device shown in Figure 1 taken on the line 2--2.

Figure 3 is a plan view of the parts shown in Figure 2.

Figure 4 is a view similar to Figure 2

showing the parts in a relatively closed position.

Figure 5 is a view similar to Figure 2 showing a modified form of the invention.

Figure 6 is a view in horizontal section taken on the line 6--6 of Figure 5.

Referring to the drawings for a more detailed description of the invention, a collapsible tube container 10 is shown in Figure 1, the container being provided with a dispensing top 11 to which the invention hereinafter described is directed. The dispensing top 11 of the container 10 is made up of a discharge nozzle member 12 formed integrally with the shoulder 13 of the container and which has a conical formation provided with an annular groove or indentation 14 to provide a shoulder or enlargement 15 at the base of the conical member.

A closure or cap member 16 is provided which is mounted in enclosing relation to the nozzle member 12 and which has the annular edge thereof crimped or upset into engaging relation with the annular recess 14 formed in the nozzle member 12. The relation of the cap or closure member 16 to the nozzle member 12 is such that the member 16 can be rotated on its seat through an angle or part of a revolution indicated by the arrows in Figure 3 of the drawing.

The nozzle member 12 is provided with a discharge opening 18 which takes the form of an elongated slit extending axially of one of the faces of the conically-shaped nozzle member. A corresponding port or opening 19 is formed in the cap or closure member 16, the opening 19, however, being somewhat smaller in its lateral direction than the opening 18 in the nozzle member 12. The opening 19 in the cap member 16 is adapted to be brought into or moved out of register with the opening 18 in the nozzle member 12 upon rotation of the cap member 16 in the manner described.

In order to bring about a desired or necessary sealing effect which will completely close the openings in the dispensing member when in inoperative position, the dispensing top portion of the container is formed in an unsymmetrical or eccentric formation as is clearly shown in Figures 2, 3 and 4 of the drawing. Referring again to

Figure 2 of the drawing it will be seen that the cap member 16 is so disposed that the opening 19 therein is in alignment or register with the opening in the nozzle member 12. With this disposition of the parts it will be seen that the base portion of the cap member 16 is spaced symmetrically about its length from the corresponding shoulder or base portion 15 of the inner nozzle member 12. On the other hand, referring to Figure 4 of the drawing, it will be seen that when the cap or closure member 16 has been rotated through a position such as will remove the port 19 from registration with the port 18, the base portion of the cap member 16 is brought into close contact or engagement with the base portion of the nozzle member 12 in the vicinity of the port 18 while at the opposite side of the top member the cap member 16 is spaced at a slightly increased distance from the enclosed base portion 15 of the nozzle member 12.

The general result of this disposition of parts is to force the inner surfaces of the cap member 16 which lie adjacent to the port 19 into close engagement with the contiguous outer surfaces of the nozzle member 12. This has the effect of producing a tight or closely fitted relation of the parts which provides an effective sealing effect and prevents evaporation of volatile constituents of the contents of the container when the dispensing top is turned to inoperative position.

Reference has already been made to the smaller size of the port 19 in the cap member 16 as compared with the size of the port 18 in the nozzle member 12. The purpose of this is to provide a non-registration of the edges of the openings 18 and 19 as is clearly shown in Figure 3 of the drawings, when the ports are in registering positions. By this arrangement a pronounced shearing or cutting effect is achieved upon the region of material extending through the ports at the termination of a dispensing operation of the containers. This shearing operation is rendered particularly clean-cut by the non-registration of the parts referred to so that a clearing action of the ejected material is provided which prevents the accumulation of residues or remnants of material in or about the discharge ports.

In order to facilitate the operation of rotating the cap or closure member 16 the outer surface of the cap member 16 is preferably longitudinally corrugated or grooved as at 20 to facilitate grasping of the closure member by the fingers of the user.

In Figures 5 and 6 of the drawing there is shown a modified form of the invention wherein the parts are shown in a symmetrical or conical relation as distinguished from the unsymmetrical or eccentric relation as shown in Figures 1 to 4 of the drawing.

In this form of the invention the nozzle member 21 has a truly symmetrical, conical formation and the cap or closure member 22 which is fitted in rotative relation to the nozzle member 21 has, in like manner, a 70 conical formation such that the cap member 22 can be rotated through a full movement of revolution about the nozzle member 21 upon which it is seated. While this form of the invention does not provide the special 75 seating effect achieved in the construction shown in Figures 1 to 4 of the drawing, nevertheless, the dispensing top or closure thus provided is capable of useful application and is a substantial improvement over 80 devices for this general purpose heretofore known and used.

What I claim is:—

1. In a dispensing closure member for collapsible tube containers, an outwardly converging nozzle member having an elongated port in a side wall thereof, a cap member rotatably mounted in enclosing relation to the nozzle member and having a port arranged to be placed in registration with the port in the nozzle member, said nozzle member and said cap member being unsymmetrically formed whereby relative rotation of the parts to non-discharging position will produce a sealing effect. 95

2. In a dispensing closure member for collapsible tube containers, an outwardly converging nozzle member, a cap member rotatably mounted in enclosing relation to the nozzle member, said nozzle member and said cap member being unsymmetrically formed, and the walls of said members being provided with discharge ports in the sides thereof having the shortest length from base to tip. 100

3. In a dispensing closure member for collapsible tube containers, an outwardly converging nozzle member, a cap member rotatably mounted in enclosing relation to the nozzle member, said nozzle member and said cap member being inclined in a lateral direction, and the side walls of said nozzle member and said cap member being provided with ports in the side toward which the members are inclined. 115

4. In a dispensing closure member for collapsible tube containers, an outwardly converging nozzle member having a circumferential groove in its base portion, a cap member rotatably mounted in enclosing relation to the nozzle member and having its edge portion engaging said groove to hold the cap member in position, said nozzle member and said cap member being inclined in a lateral direction, and the side walls of said nozzle member and said cap member being provided with ports in the side toward which the members are inclined. 120

5. In a dispensing closure member for collapsible tube containers, an outwardly con- 130

verging nozzle member having a circumferential groove in its base portion, a cap member rotatably mounted in enclosing relation to the nozzle member and having its edge portion upset into engagement with said groove to hold the cap in position, said nozzle member and said cap member being inclined in a lateral direction, the side walls of said nozzle

member and said cap member being provided with ports in the side toward which the members are inclined, said ports extending axially of said members and the port in the cap member being of less width than the width of the port in the nozzle member.

In testimony whereof I affix my signature.
SIGMUND GREENFIELD.
